UNITED STATES PATENT OFFICE.

ALONZO HARRIS, OF MATTOON, ILLINOIS, ASSIGNOR OF ONE-HALF TO
OTTO SCHILLING, OF MATTOON, ILLINOIS.

CAR-WHEEL SHOE.

No. 834,298.

Specification of Letters Patent.

Patented Oct. 30, 1906.

Application filed June 15, 1906. Serial No. 321,807.

To all whom it may concern:

Be it known that I, ALONZO HARRIS, a citizen of the United States, residing at Mattoon, county of Coles, and State of Illinois, have invented certain new and useful Improvements in Car-Wheel Shoes, of which the following is a specification.

The object of this invention is to provide a slideable shoe adapted for the transportation of cars crippled by broken wheel-flanges or loose wheels or otherwise unfit to be moved along on their own wheels; and the object of the invention is to provide a shoe which can be slid along the track through a frog or switch or around any curve and which will support and retain the wheel in its transportation to the shops for the purpose of repair or otherwise.

The shoe is intended to receive and lift the wheel bodily off the track-surface, so that the car will be transported without the turning of the wheel.

The shoe is so arranged that the wheel can be positioned in place and held therein without the necessity for providing chains, rods, or other attaching means, which greatly facilitates the operation of transporting cars by means of the device of the present invention.

The invention consists in the features of construction and combination of parts hereinafter described and claimed.

In the drawings, Figure 1 is an inside elevation of the shoe, showing the wheel mounted thereon; Fig. 2, a top or plan view of the shoe, and Fig. 3 a cross-sectional view of the same.

The shoe is of elongated formation, provided at its forward end with an elevation or abutment 1, having a sloping forward end 2 and an inwardly-rounded inner face 3, having a curvature conforming approximately to the curvature of a car-wheel. The forward or elevated end of the shoe terminates in a substantially flat intermediate portion 4, having a flat face 5, which in turn terminates in a sloping rear end portion 6, having an inclined or sloping face 7. The shoe throughout its entire length is provided along its inner edge with a groove 8, which conforms to the shape of the shoe and is of a suitable size to receive the flange 9 of a car-wheel 10. The shoe is of sufficient width to entirely cover the top of a rail, allowing the grooved portion to inwardly extend from the

rail, and the shoe is provided with a pair of flanges 11, adapted to abut against the inner edge of the rail-head, which flanges are of substantially the same thickness as the car-wheel flange, which allows them to travel through all frogs or switches which are of a suitable size to permit the passage of a car-wheel.

In addition to the inner flanges 11 an outer flange 12 is provided, which is located near the forward end of the shoe on the outer side thereof and is adapted to abut against the outer face of the car-wheel, and this arrangement of flanges and in combination with the inner side groove 8 serves to lock or hold the shoe on the rail when the car-wheel is rolled thereon, so that the shoe cannot be displaced under any circumstances.

In use the car-wheel is rolled or lifted onto the shoe until it abuts against the curved inner face, after which the car may be pulled along by the engine, and the shoe will slide or slip along the rail during the progress of the car to the repair-shops. The elevation of the forward end of the shoe is sufficient to prevent the wheel from rolling up and over the shoe, and the shoe is prevented from being inwardly displaced from the rail by the contact of the outer flange 12 against the car-wheel, and the contact of the wheel-flange 9 against the wall of the side groove 8 likewise prevents the outward displacement of the shoe which is positioned on the rail by the contact of the inner flanges 11 against the inner side of the rail-head. This arrangement obviates the necessity for providing any means for securing the wheel in position on the track, and the length of the shoe is sufficient to prevent its easily wearing out by friction, since the weight of the wheels is distributed over a considerable distance.

The device as a whole is of extreme simplicity and corresponding durability, which, in addition to the ease with which it can be used, renders it peculiarly fit for the purpose intended.

What I regard as new, and desire to secure by Letters Patent, is—

1. A shoe of the class described, having an elevated forward end having the contour of its inner face coincident with the curvature of a car-wheel to receive and closely embrace the tread of a car-wheel, and having at its rear end an inclined portion for permitting

the mounting thereon of a car-wheel, substantially as described.

2. A shoe of the class described, having an elevated forward end having the contour of its inner face coincident with the curvature of a car-wheel to receive and closely embrace the tread of a car-wheel, and having at its rear end an inclined portion for permitting the mounting thereon of a car-wheel, and provided along its inner outer edge with a groove adapted to receive the flange of a car-wheel, substantially as described.

3. A shoe of the class described, having an elevated forward end having the contour of its inner face coincident with the curvature of a car-wheel to receive and closely embrace the tread of a car-wheel, and having at its rear end an inclined portion for permitting the mounting thereon of a car-wheel, and provided along its inner upper edge with a groove adapted to receive the flange of a car-wheel, and provided on its outer edge with a flange adapted to abut against the outer face of a car-wheel, substantially as described.

4. A shoe of the class described, having an elevated forward end having the contour of its inner face coincident with the curvature

of a car-wheel to receive and closely embrace the tread of a car-wheel, and having at its rear end an inclined portion for permitting the mounting thereon of a car-wheel, and provided along its inner upper edge with a groove adapted to receive the flange of a car-wheel, and provided on its outer edge with a flange adapted to abut against the outer face of a car-wheel, and provided on its inner lower edge only with a flange adapted to abut against the inner side face of a rail-head, substantially as described.

5. A shoe of the class described, having an elevated forward end and curved on its inner face to receive and closely embrace the tread of a car-wheel and having a rearwardly-extending elongated body portion terminating in an inclined portion adapted to elevate a car-wheel, a groove along the inner upper edge adapted to receive the flange of a car-wheel, and a depending flange adapted to bear against the inner side face of a rail-head, substantially as described.

ALONZO HARRIS.
